UNITED STATES PATENT OFFICE

LOUIS H. HOSBEIN, OF CHICAGO, ILLINOIS, ASSIGNOR TO M. H. DETRICK COMPANY, OF CHICAGO, ILLINOIS, A CORPORATION OF ILLINOIS

FURNACE CONSTRUCTION

Application filed July 5, 1923. Serial No. 649,472.

This invention relates to furnace construction, and pertains particularly to improvements in the construction and assembly of parts comprising and associated with the structures forming the top closure for the furnace chamber and commonly referred to as the "furnace arch".

The invention relates to that type of furnace arches commonly designated "suspended arches" to distinguish from "sprung arches". The use of suspended arches in various sorts of furnaces is becoming rapidly more general, and arches of that type are recognized as possessing certain distinct features of advantage over other types. It is one of the purposes of the present invention to incorporate certain improvements into the construction of arches of this type, or into furnace parts associated with arches of this type, while maintaining all of the recognized advantages which suspended arches possess.

The general purpose of the invention is the provision of improved construction designed to better the stability of furnace structures and increase the term of service of suspended arches and other refractory portions associated with them.

Another object of the invention is the provision of a construction designed particularly to accommodate the expanding and contracting movement of the arch in response to changes in temperature, without opening joints between the arch and portions of the setting with which it is associated.

Another object is the provision of a construction of increased flexibility in the particular that it may be readily accommodated to varied conditions in the furnace or boiler setting.

A further object of the invention is the provision of a construction whereby the arch and superjacent curtain wall structures are associated in such fashion as to facilitate repair of the respective parts independently.

Another specific object of the invention is the provision of a construction whereby the arch may contribute to the support of the curtain wall without subjecting the arch structure itself to the weight of the curtain wall.

A further object of the invention is a provision of improvements in suspended arch construction whereby arches of that type are adapted to the particular requirements imposed by very wide furnaces. 55

Another object is the improvement of the ignition arch construction and arrangement for grate fired furnaces, such as those employing chain grate stokers, with the purpose of obtaining improved fuel ignition and heat reflection and combustion. 60

Other and further objects of the invention will be pointed out hereinafter, indicated in the appended claims or ascertainable from the present disclosure by one skilled in the art. 65 It will be observed that for the purpose of this application I have disclosed herein one form in which the invention may be embodied, but it is to be understood that the same is here presented for the purpose of illustration only, and hence that it is not to be accorded any interpretation having the effect of limiting the invention which I purport to secure hereby, short of its true and most comprehensive scope in the art. 70

In the accompanying drawings, forming a part of this specification, Fig. 1 represents a longitudinal sectional elevation taken through the upper portion of a furnace embodying my invention, parts illustrative of the stoker mechanism being shown diagrammatically. 75

Fig. 2 is a top view such as would be observed on line 2—2 of Fig. 1.

Fig. 3 is a detail in the nature of a perspective illustration of one of the wall brackets. 85

The nature of the invention will best be understood by reference to these drawings in detail, whence it will be observed that the reference character 10 designates side walls which define the lateral limits of the furnace chamber and which, in the present instance, are illustrated as constituting supports for the arch structure. One of the advantages of the present construction, however, is that the arch and curtain wall structure may be supported independently of the side walls as on suitable columns, so that the side walls may be relieved of that load. The parts des- 90 95 100 105 110 115 120 125 130 135 140 145 150 155 160 165 170 175 180 185 190 195 200

gnated by reference characters 11 and 11a are intended to illustrate parts representing the grate and hopper of a chain grate stoker mechanism by which fuel is fed into the furnace chamber through the feed inlet 12. The invention is not limited for its utility, however, to use with any particular stoking mechanism, or to automatically stoked furnaces. At the front of the furnace there is 10 a transversely extending beam 14, which is here illustrated as formed of conjoined channel and I-beam members; and at the rear portion of the arch a transversely extending span beam 15, here illustrated as formed of 15 rigidly conjoined I-beam members. Both of these beams 14 and 15 span the furnace chamber, and are supported at their ends on the furnace walls 10 or otherwise. They preferably are spaced at a substantial distance 20 from the location of the refractory arch portions which close the furnace chamber. Extending between these two beams 14 and 15, and connected at its extremities thereto, is a stay member or carrier beam, 16. There may 25 be a plurality of these, depending on the width of the furnace or other considerations. Supported on the carrier beam 16 are the hanger beams 17, which extend transversely of the furnace intermediate the beams 14 and 30 15. By means of hangers 18 shiftably carried on the hanger beams 17, tile supports 19 are suspended above the furnace chamber, said supports preferably taking the form of arch bars extending longitudinally of the 35 furnace chamber and provided with tile retaining portions, here illustrated as laterally directed flanges 19a. Tile 20 are suspended on these tile supports with their side faces in contact so that in their association they form 40 a continuous flat closure roof or arch for the furnace chamber. As a means for protecting the stoker mechanism, or improving the operation of the furnace, a front drop arch of the form illustrated may be employed, although the use of such a construction is not 45 essential to other features of my invention herein claimed. Features of this drop arch or ignition arch construction form the subject matter of and are claimed in the patent 50 of myself and Nathaniel D. Stevens, Number 1,628,284, and my U. S. Patent 1,544,580. In the embodiment herein illustrated, however, the drop arch construction includes 55 certain new and advantageous features not included in the earlier patents. The new construction includes a series of drop hangers 21 suspended across the front of the furnace from the beam 14, said drop hangers being provided with upwardly deflected tile 60 retaining portions 21a on which are hung wedge shaped tile 22 to form a convex refractory arch portion depending into association with the fuel inlet. In association with these wedge shaped tile, one or more 65 parallel faced tile 24 are similarly suspend-

ed on each of the drop hangers, their lateral faces contacting side faces of juxtaposed tile, and their end faces forming continuations of the conyex arch surface formed by the end faces of the wedge shaped tile. 70 Above the tile 24 are disposed other wedge shaped tile 22', also connected to the hangers 21. At a location above the position occupied by these suspended tile, the drop hangers are provided with rearwardly extending shelves 21b, which are spaced apart from the terminals of the tile retaining members 21a so as to afford clearance for the mounting and dismounting of tile on the latter. These shelves form supporting platforms for brick 23 laid thereon to form a front curtain wall, or a connecting wall between the drop arch and the top arch. In the form illustrated this connecting wall is relatively low, but in many instances it will 85 be of considerable height, and consequently of very considerable weight. The provision of the shelves 21b, in addition to permitting the removal and replacement of tile below this wall, without requiring dismantling of 90 any part of the latter, relieves the suspended tile from the weight of the wall which otherwise would be imposed upon them. Moreover, this construction relieves the wall portion of possible effects arising from differences of expansion and contraction in the drop arch and roof arch, with the result that the likelihood of opening the joint between that wall and the top arch is very materially decreased. This is a factor of great importance, when it is observed that appreciable expansion is likely to occur in the arch portion which is over the fire, while the depending ignition arch, which is nearer the fuel inlet is not likely to be subject to an equally 100 high temperature. The space between the topmost suspended tile and the lowermost tile carried on the shelf 21b is filled by filler bricks resting on the suspended tile.

It will be observed that the ignition arch constructed as above described has a relatively narrow end immediately over the fuel inlet, from which portion the arch surface rises quite quickly and steeply toward the top arch. This construction of the wall gives the desired protection for the stoker front and the front suspension beam 14, while accommodating maximum reflection of radiant heat from the top arch onto the green fuel at the fuel inlet.

It is to be observed that the construction of the top arch affords an assembly in which the individual tile are susceptible of limited relative movement. Tile supporting members 19 are suspended so that the individual courses carried by them respectively, or the entire refractory arch, may be swung laterally, longitudinally or vertically. This is one of the advantageous features of suspended arches of this type, as it enables the arch 120 125 130

to accommodate expansion and contraction in its component parts without injurious strain upon either them or the associated parts of the furnace construction, such as 5 the side walls. At the rearward end of the flat arch I prefer to employ fan end or arcuate arch nose construction of the general sort illustrated in and claimed in my U. S. Patent 1,544,580 above specified, or of the sort 10 described and claimed in the patent of myself and Raymond D. Foltz, Number 1,628,318. The construction here shown includes nose brackets 25 attached to the rearward end of the tile supporting members 19, 15 upon which nose brackets wedge shaped tile 26 are suspended to form an upwardly curving convex end arranged to guide the products of combustion upwardly to the boiler passes. With this rear end, in such fashion 20 as to form an upward continuation thereof, is usually associated a curtain or apron wall which forms a closure between the arch and the forward portion of the boiler setting. When this curtain wall is of comparatively 25 small vertical extent it may be carried on the rear end of the suspended arch. In instances in which the apron wall is high and heavy, the imposition of its weight upon the rear end of the suspended arch may impose too 30 much weight upon the arch hangers, and tend to rotate the arch on a horizontal axis, with the resulting tendency of the forward end of the arch to separate from the drop arch, or open the joint at the forward margin 35 of the top arch. As a means for obviating these tendencies, and for removing undesirable restricting or opposing limitations to the self-adjusting movements of the arch, I provide a plurality of wall brackets 27, 40 a form of which is illustrated in detail in Fig. 3. Preferably each bracket has a shelf portion 27a at the rearward end of a bar-like body portion strengthened by marginal flanges 27b and equipped with a hook-like 45 portion 27c spaced from its forward extremity and adapted to hook over the lower flange of the span beam 15. The bracket also may be provided with a retaining member 27d adapted to engage the span beam to prevent 50 displacement of the hook portion 27c from its flange. When positioned on the span beam, the bracket forms a cantilever fulcrumed on the hook portion 27c and with the part forward thereof contacting the bottom 55 of the beam to hold the rearward portion against downward rotation. As illustrated in Fig. 2, these wall brackets are positioned on the span beam in collateral disposal and at any desired intervals. Their position 60 thus may be accommodated to the adjacent hangers 18 and to other elements of the structure. Their rearward ends project over the tile supported on the end brackets 25 and afford supports for the brick forming the 65 apron wall 28, which thus is supported inde- pendently of the suspended arch. The space between the tile 26 and the wall brackets 27 is filled with filler brick 29, removal of which permits removal and replacement of the tile 26 without requiring dismantling of any of 70 the apron wall. Likewise, the construction permits the individual removal and replacement of the wall brackets 27, or of any portion of the curtain wall, without requiring dismantling of any of the parts in the suspended arch. Inasmuch as the wall brackets 27 are independent of the tile supports, the number of brackets employed is determined entirely by the requirements imposed by the weight of the apron wall, so that the amount 80 of metal may be reduced to a minimum when the wall is light or the number of brackets increased in excess of the number of tile supports 19, if the weight of the apron wall demands it. 85

The construction, of course, is susceptible of use in various locations, as in the back arch illustrated at the right hand end of Fig. 1 wherein the tile supports 19' carry the suspended arch over the rear end of the stoker or grate, and the wall brackets support a part of the back wall or bridge wall 30. 90

An advantage of the construction resides in the fact that the entire wall above the flue end of the suspended arch may be supported entirely from a structural member such as the beam 15, while affording that member complete protection from the furnace by means of the portion of the wall carried on the brackets 27, and permitting the supporting 95 structural member to be spaced away from the refractories to afford the circulation of air necessary to prevent overheating of the metallic member. It is of particular importance in wide furnaces, in which the support 100 of the apron or curtain wall in association with high set boilers presents a difficult problem when it is desired to employ suspended arches. The stay member 16 performs an important function in the supporting of the 105 arch structure, aside from its support of the beams 17. It will be observed that by virtue of the fact that a considerable proportion of the weight of the curtain wall 28 is carried on the laterally projecting shelf members 27, that 110 the beam 15 is loaded eccentrically of its longitudinal axis, so that a moment is imparted to it which has the tendency of tilting it rearwardly. The same is in a measure true of the beams 14, which, due to the fact that it is 115 eccentrically loaded by the ignition arch members and by the apron wall 23 which is carried on the rearwardly projecting brackets 21b, is also given a rearwardly tilting moment. To counteract this loading on both the beams 14 and 15 the stay beam 16 is rigidly connected to them in such relationship that they cannot tilt under the weight of their eccentric loads, 120 said beams 14 and 15 exercising reciprocal bracing effects upon each other through the 125 130

instrumentality of the stay beam 16. By virtue of the construction, therefore, the ignition arch and the curtain wall 28 are maintained in fixed relation with respect to each other, while the top arch is maintained flexibly suspended in the desired relation to them to form an intervening closure. The construction is of particular utility by virtue of the fact that while it provides this stability of support for the refractories, the metallic supporting members are arranged in such relation to the refractories that they are afforded ample ventilation, and thereby protected against destructive overheating.

15. What I claim is:

1. In a travelling grate stoker furnace, an ignition arch comprising frame members, wedge shaped refractories connected at their narrower ends thereto and spaced apart vertically, and other refractories having parallel sides disposed between the wedge shaped refractories and cooperating therewith to form a wall sloping inwardly and upwardly from the fuel inlet.

25. 2. In a furnace, an arch structure comprising frame members, wedge shaped refractories connected thereto at their narrower ends and spaced apart vertically, and parallel sided refractories connected to the frame members and filling the space between the wedge shaped refractories and cooperating therewith to form a refractory wall extending inwardly and upwardly in the furnace chamber.

35. 3. In chain grate furnace construction, frame members, wedge shaped refractories connected thereto at their narrower ends and spaced apart vertically, and other refractories having parallel sides interposed between the wedge shaped refractories and connected to the frame members, the outer ends of the wedge shaped and other refractories forming a wall surface sloping inwardly and upwardly from the fuel inlet.

45. 4. In a chain grate furnace, the combination with a top arch, of frame members arranged between the same and the fuel inlet, wedge shaped refractories connected at their narrower ends to said frame and spaced apart vertically, and other refractories having parallel sides interposed between the vertically spaced wedge shaped refractories and connected to the frame, the outer ends of the wedge shaped and other refractories forming a steeply inclined wall surface sloping inwardly and upwardly toward the top arch from the fuel inlet.

55. 5. In a grate fired furnace an ignition arch construction comprising, in combination, a frame, wedge shaped refractories and parallel sided refractories suspended therefrom with their end surfaces merging to form a wall surface sloping sharply upwardly from the grate.

65. 6. In a grate fired furnace, an arch construction comprising wedge shaped refrac-

tories, parallel sided refractories interposed between the wedge shaped refractories, and securing means cooperating with the outer ends of said refractories to hold their inner ends in alignment to form a heat reflecting surface sloping steeply upwardly from the grate.

7. In furnace construction, the combination with a top arch, of drop hangers depending therefrom above the fuel inlet, wedge shaped tile suspended from said drop hangers to form a radial arch portion rising toward the top arch, and parallel sided tile suspended on said drop hangers to form a straight continuation from the radial arch portion, the inner end surfaces of the wedge shaped and parallel sided tile cooperating to form a regular and uninterrupted refractory surface sloping upwardly from the fuel inlet toward the top arch.

8. In furnace construction including a top arch, a beam arranged adjacent the margin of the top arch, drop hangers suspended on said beam and depending below the top arch, tile suspended on said drop hangers to form a depending arch portion, shelves supported on said drop hangers, and refractories supported on said shelves intermediate the depending arch portion and the top arch.

9. In furnace construction including a top arch, a series of drop hangers supported adjacent a margin of the top arch, tile suspended on said drop hangers to form a depending arch portion below the top arch, shelves supported on said drop hangers, and refractories supported on said shelves to form a wall portion conjoining the top arch and the depending arch portion.

10. In furnace construction, including a top arch, drop hangers supported adjacent the margin thereof, tile suspended on the drop hangers in association to form a depending arch portion, shelves supported on said drop hangers above the tile, and refractories supported on said shelves to form a wall portion intermediate the depending arch portion and the top arch, tile being removable from the drop hangers without requiring displacement of said refractories.

11. In furnace construction, the combination of a supporting beam disposed above a portion of the furnace, a shelf member supported thereon and extending laterally thereof, a wall portion carried on said shelf, and a stay member secured to the beam to afford a counterpoise to the weight of the shelf and supported wall portion.

12. In furnace construction, the combination of a beam extending transversely of the furnace, a wall portion carried on said beam and loading same eccentrically and a stay member secured to the beam and extending forwardly over the furnace structure and adapted to resist the tilting moment imparted to the beam by the weight of the wall portion.

13. In furnace construction, the combination of a beam extending above the furnace, a shelf member supported thereon and extended laterally therefrom, a wall portion supported by said shelf member, a stay member secured to the beam and extending oppositely to the shelf member, and an arch suspended from said stay member in association with the wall portion, whereby the weight of the arch and the wall portion are transmitted to the beam as opposing moments.

14. In furnace construction, the combination of a beam extending transversely of the furnace, a shelf member supported on and extending laterally from said beam, a wall portion supported on the shelf member, a stay member extending longitudinally of the furnace and connected to the beam, whereby to resist the tilting moment imparted by the weight of the wall portion, and an arch portion sustained by said stay member in association with said wall portion.

15. In furnace construction, the combination of beams extending in substantially parallel relationship, a shelf member supported on and extending laterally from a beam, a wall portion carried on said shelf member, and a stay member rigidly connected with the beams, whereby they cooperated to sustain the wall portion.

16. In furnace construction, the combination of beams supported at forward and rearward portions of the furnace, a shelf supported on and extending laterally from a beam, a wall portion carried on said shelf, a stay member connecting the beams in relationship to resist the tilting moment imparted by the weight of the wall, and arch portions sustained by said beams and stay member in association with said wall portion.

17. In furnace construction, in combination, collaterally arranged hangers, wedge-shaped refractories supported at the lower ends thereof, and parallel-sided refractories anchored to the hangers with their upper and lower parallel faces in sloping position and parallel to upper faces of the wedge-shaped refractories and with the inner faces of said wedge-shaped and parallel-sided refractories cooperating to form an arch surface sloping upwardly from the lower end of the structure.

18. In furnace construction, in combination, a transverse beam across a rearward portion of the furnace chamber and constituting an eccentrically loaded support for a portion of the refractory structure of the furnace, means supporting said beam at its ends, a stay beam connected to said transverse beam and extending therefrom over a portion of the furnace chamber, and a roof arch suspended below the stay beam and having a portion of its weight sustained thereby, whereby said stay beam and weight

of the arch portion are adapted to oppose the turning moment exerted on the transverse beam by its eccentric load.

19. In a furnace installation, in combination, a transverse beam disposed over a forward portion of the furnace, a transverse beam spanning a rearward portion of the furnace chamber, a stay beam extending longitudinally over a portion of the furnace and connecting said transverse beams, a wall structure supported by the rearward transverse beam, transversely extending members supported in part by the stay beam, an arch nose structure supported from the rearward transverse beam, hangers depending from the transverse members, and a roof arch suspended by said hangers below the stay beam and transverse members and in conjoining relationship with the arch nose.

In testimony whereof I have hereunto signed my name.

LOUIS H. HOSBEIN.
